[57] CLAIM

The ornamental design for a packaging container for food and beverages, as shown and described.

DESCRIPTION

FIG. 1 is a perspective view of a packaging container for food and beverages showing our new design; FIG. 2 is a top plan view thereof; FIG. 3 is a front elevational view thereof; FIG. 4 is a bottom plan view thereof; FIG. 5 is a rear elevational view thereof; FIG. 6 is a view looking from the left of FIG. 3; FIG. 7 is a view looking from the right of FIG. 3; FIG. 8 is a perspective view with the tear away panel removed, the top stop means folded in and a beverage cup being shown in broken lines to illustrate environmental use only; FIG. 9 is a top plan view thereof; FIG. 10 is a front elevational view thereof; FIG. 11 is a rear elevational view thereof; FIG. 12 is a view looking from the left of FIG. 10; and FIG. 13 is a view looking from the right of FIG. 10. The dash lines and dotted lines on the container represent score lines.
